United States Patent Office

Des. 183,182
Patented July 8, 1958

183,182

RADIO CABINET

Jean O. Reinecke, Oak Park, Ill., assignor to Zenith
Radio Corporation, a corporation of Illinois

Application January 23, 1957, Serial No. 44,571

Term of patent 7 years

(Cl. D56—4)

Fig. 1

Fig. 2

Fig. 3

Fig. 4

Figure 1 is a front elevational view of a radio cabinet showing my new design;

Figure 2 is a top plan view;

Figure 3 is a side elevational view; and

Figure 4 is a right side view with the central portion of the cabinet shown partially in section.

The rear of the cabinet is unornamented.

I claim:

The ornamental design for a radio cabinet, substantially as shown and described.
